UNITED STATES PATENT OFFICE.

THOMAS R. HAYES AND LAWRENCE E. KITSON, OF PORTLAND, OREGON.

BALL-RACK.

1,345,769.

Specification of Letters Patent.

Patented July 6, 1920.

Application filed February 20, 1919. Serial No. 278,274.

To all whom it may concern:

Be it known that we, THOMAS R. HAYES, a citizen of Canada, and LAWRENCE E. KITSON, a citizen of the United States, each residing at Portland, in the county of Multnomah and State of Oregon, have invented a new and useful Improvement in Ball-Racks, of which the following is a specification, reference being had to the accompanying drawings.

Our invention relates to a class of devices used to hold billiard and pool balls particularly.

The object of our invention is to provide a device of this kind wherein mechanism is arranged automatically to register the number of games played and the number of players in each game, as the balls are removed or the racks opened for players. We attain these objects, as well as other advantages, by the construction, combination and arrangement of parts illustrated in the accompanying drawings which form a part hereof.

Figure 1 is a front elevation of the device with parts broken away.

Fig. 2 is a right end elevation.

Fig. 3 is a sectional view on the line 3—3 in Fig. 1.

Fig. 4 is a like view on the line 4—4.

Fig. 5 is a sectional plan view on the line 5—5 in Fig. 1.

Fig. 6 is a front elevation of the device with parts broken away and showing racks adjustable in horizontal position.

Fig. 7 is an elevation of a key used in operating the mechanism.

Fig. 8 is a sectional view on the line 8—8 in Fig. 6.

Like letters and numerals refer to like parts in the views.

A casing A of desired form and dimensions is provided, having longitudinal, inclined ball racks B therein. A receiving receptacle, or basket C, is suspended from the casing below the lower ends of the racks B. The upper ends of the racks have openings 9, through which balls 10 may be passed into the racks. Within the casing a vertical slide 11, having an opening 11' from a recessed lower part thereof, is arranged adjacent to the lower ends of the ball racks. This slide has openings 12, of a size which will allow the balls 10 to pass through them from the

rack opposite, and the slide is positioned a sufficient distance from the opposing end wall of the casing to allow space for the balls to drop downwardly therein and without the casing into the basket C, through the openings 13 in the bottom of the casing. Above the uppermost rack a partition 14 is placed. Near the upper ends of the partition 14 and the racks below it, except the lowest one, tumbling catches 15, of right angle form are pivoted in their centers by transverse pivots 15' in and near the ends of said parts and at a desired distance from the casing end. A stop pin 16 is placed transversely in said parts beneath the horizontal arm of each catch. A vertical slide 17 is arranged within the casing and between its wall and the upper ends of the racks B. The slide is of a length to allow it to be raised within the casing above the entrance to the uppermost rack, and it is held above the two lower racks at all times. It has dogs 18 on its inner surface and a lifting handle 19 on its outer surface at the lower end. The end of the casing is open opposite the upper ends of the ball racks. A registering mechanism to register the number of racks above the two lower ones as used by players is arranged within the casing. This consists of a register 20, positioned above the racks on a shelf 30', a lever means 21 connected with and extending from the register and arranged to allow the dogs 18, in their upward movement, to engage the free end of the means 21 and cause the register to tally, also to allow the dogs to pass below said means without affecting the register. Mechanism is provided to retain the slide 17 at a desired height and to release it, which will be now described.

There is a horizontally movable rod 22, having one end in position to engage recesses 23 in the inner surface of the slide 17, also having a lug 24 in a desired position thereon. Brackets 25 are provided to retain the rod 22 in alined position. There is a lever 26 horizontally movable and pivoted on a pivot 27 near the opposite end of the rod 22. One end of the lever 26 is forked and engages a pivot pin 28 in the adjacent end of the rod 22, the free end of the lever being positioned so it can be moved forwardly when a cam plate 29 on the slide 11 engages it, which will cause the rod 22 to move rearwardly. A spring 30 is secured at

one end to the lever 26 between its forked end and its pivot, the opposite end of the spring being secured to the shelf 30' at a point 31 toward the slide 17. A vertically 5 movable rod 32 is arranged parallel with the inner surface of the casing wall 33 in a position where its lower end will rest upon a key socket 34, which extends through an opening 34' in the casing wall 33, below the racks, which opening is large enough to allow an 10 upward movement of the socket. The socket 34 has an opening 35 therein and a pin connection 36 to the rod 32 also a heel 37 at its inner end. The rod 32 has a cam plate 38 15 on its upper end in position to engage the lug 24. A vertical spring 39 is secured at its lower end upon the inner surface of the casing floor by a screw 40, the upper end of the spring having a cam shoulder 41 formed and 20 arranged to slide upon and engage the upper surface of the socket heel 37. The spring 39 has a horizontal pin 42 which extends therefrom through the opening 35 and within the socket 34. The pin has a collar adjacent to 25 the spring to retain the pin loosely within the spring and allow the pin to be raised slightly.

Mechanism to register games is provided, which will be now described.

30 A key socket 43 extends through an opening 44' in the casing wall 44, said opening being large enough to allow the socket to move upwardly. The socket extends into a recessed lower part of the slide 11. The 35 socket is secured to the slide 11 by a screw 43'. A horizontal pin 46 extends from within the recessed part of the slide 11 through the opening 11' and into a recess 46' in the opposite casing wall. A pivot pin 49 40 is secured upon the opposite end of the pin 46. A vertical arm 47 is pivoted in its center upon a rigid pivot 48 within the slide 11 the lower end of the arm being pivoted on the pin 49. The upper end of the arm 47 is 45 pivoted upon a pivot 49' of the inner end of a horizontal key bar 50 which extends therefrom through the opening 45 and within the key socket 43. A spring 50' is secured at one end upon and near the upper end of the 50 arm 47 and its opposite end is secured to the outward part of the slide 11. A register 51 is secured upon the upper surface of the shelf 30' at a desired distance from the upper end of the slide 11. It has a register 55 operating lever arm 52, bearing a transverse pin 52' in its upper end. A vertical standard 53 is secured at its lower end upon the shelf 30' between the register and the upper end of the slide 11. A transverse arm 54 is 60 pivoted in its center upon a pin 55, transversely positioned in the upper end of the standard 53. The arm 54 has slots 56 and 56' in its respective ends. The pin 52' extends through the slot 56. A bar 57 is secured at its lower end upon the slide 11 by

screws 58. The bar 57 has a transverse pin 59 on its upper end, which extends through the slot 56' of the arm 54.

A key 60 with a recess 61 in its end is provided to insert in the sockets 34 and 43 to engage the pins 42 and 50 respectively. 70

A horizontal, hinged cover 62 is provided upon the upper part of the casing to inclose the registering mechanism above the shelf 30'. The cover 62 has locking means 63. 75

There must always be at least two players, hence the two lower racks in the device are never closed. When a game is tallied upon the register 51 it always includes the first two, or two players only. The number of 80 players in excess of the first two is always shown by the register 20. When two players only are using the device in the two lower racks the balls may be inserted in the rack appropriate to each but cannot be removed therefrom because of the tumbling catches 15 preventing removal. The balls thus used cannot be taken from the lower end of the racks until the key is inserted, by the operator in charge, within the socket 85 43 and movement of the intervening mechanism allowed.

This mechanism is actuated by causing the key to release and raise the socket and it in turn to raise the slide 11 which releases the balls and they pass out of the racks and drop into the basket. The same movement of the key causes the intervening mechanism to operate the register 51 for a game tally. The key is then withdrawn, 100 the slide 11 closes the racks automatically, and the apparatus is ready for another game and reception of balls as before.

It will be seen also that when more than two players are using the racks, the key is 105 inserted in the socket 34, pressed rearwardly and then raised. This operates the intervening mechanism and releases the locked slide 17 which is then raised to open as many of the upper racks as are desired for 110 excess players. When so raised the key is withdrawn and the slide is locked automatically in the desired position, while the opened racks are used in the same manner as already described for two players. 115 When the slide is thus raised the dogs 18 engage the lever mechanism 21 in succession and it automatically causes the register 20 to tally each closable rack as it is opened. When a game is played with excess players, 120 the slide 17 is released when the game is tallied by use of the key to release the balls as aforesaid, by reason of the ball release slide 11 engaging the lever arm 26 and it in turn through intervening mechanism releasing the slide 17 so that it drops automatically to its lowest position shown in Fig. 1. It is obvious that the actual number of games played is always tallied when 125 the balls are removed from the racks for 130

further play. The device is particularly adaptable to pool games which require a large number of balls and in which several players may participate and the balls must be removed from a pool table to a rack to compute individual scores. It is also obvious that where players are charged an individual price for playing, the register tally of players is necessary. It is to obtain this tally and prevent further use of the balls until a game is finished that we have arranged our device as illustrated. By the game register the operator has useful information as to whether a small or large number of players have participated in any given number of games during a period for which it is computed. It is further obvious that the total number of players must be obtained by adding two for each game to the total number shown by the register 20.

In Figs. 6 and 8 we have shown a means of retaining the racks in horizontal position during a game if desired. It is accomplished by making a rigid member 64 therein, corresponding to the slide 11, and pivoting the racks on pivots 65 at one end. The opposite ends are secured to vertical side bars 66. A yoke 67 is formed on the upper ends of these bars and is attached to the game registering mechanism and operated by similar mechanism below as in the other form. A catch 68 or any desired means to hold the bars 66 when raised and to allow them to be released by the key, is provided. In this arrangement there is a reversal of the operation only. They key is inserted to raise the racks and the balls cannot pass out. When the game is finished the mechanism is operated to drop the racks. This allows the register to tally and the balls to pass out as before. We have described this form only to indicate that it does not change the principle of our invention in any way.

Our invention provides a most convenient and efficient means of tallying games and players in games, for the purpose of computing cash receipts therefor. It is apparent that errors cannot occur, as the racks must be tallied for each player and the balls in a rack cannot be released after deposit without tallying a game played. The

mechanism is also simple and easy of operation, leaving the balls always visible for inspection during a game in the usual manner.

We claim—

1. In a ball rack provided with a casing, the combination therein of a plurality of racks adapted at one end to receive balls of desired diameter, a vertically movable slide adjacent to the receiving ends of said racks, the slide being provided with dogs upon its inner face and recesses therein opposite the closable racks, a slidable rod positioned to engage the slide in its recesses and having a spring to retain it in such engagement, and a lug upon the rod, a vertically movable rod having a cam plate on its upper end arranged to engage the lug on the slidable rod and move the rod out of engagement with the slide and to release it into engagement therewith, means to lock, unlock and raise or lower said vertical rod, and a register provided with mechanism extending therefrom toward the said slide and arranged in a manner whereby the dogs upon the slide, when moving upwardly, will engage said mechanism and by its means cause the register to tally and may pass said mechanism, when moving downwardly, without causing the register to tally. 80

2. In a ball rack provided with a casing, the combination therein of a plurality of racks adapted at one end to receive balls of a desired diameter, a vertically movable slide, adjacent to the opposing ends of said racks, provided with openings therein through which balls may pass out of the racks when the openings are opposite thereto and arranged so that the slide shall prevent their passage otherwise, a register having intermediate mechanism connecting it with the upper end of the slide and by means of which the register can be caused to tally when the slide is raised to allow passage of balls through it, and means to lock, unlock and allow said slide to move vertically. 95
